UNITED STATES PATENT OFFICE

EDWIN A. BESCHERER, OF BROOKLYN, NEW YORK, ASSIGNOR TO BELL TELEPHONE LABORATORIES, INCORPORATED, OF NEW YORK, N. Y., A CORPORATION OF NEW YORK

DESIGN FOR A TELETYPEWRITER CABINET

Application filed May 2, 1933. Serial No. 47,967. Term of patent 14 years.

To all whom it may concern:

Be it known that I, EDWIN A. BESCHERER, a citizen of the United States of America, residing at Brooklyn, in the county of Kings, State of New York, have invented a new, original, and ornamental Design for a Teletypewriter Cabinet, of which the following is a specification, reference being had to the accompanying drawing, forming a part thereof.

Fig. 1 of the drawing is a perspective view of my new design for a teletypewriter cabinet;

Fig. 2 is a front view of my design; Fig. 3 is a right side view of my design; and

Fig. 4 is a top view of my design.
I claim:

The ornamental design for a teletypewriter cabinet as shown.

In witness whereof, I hereunto subscribe my name this 18th day of May, 1933.

EDWIN A. BESCHERER.
